[57] CLAIM

The ornamental design for a tub for bathing, as shown and described.

DESCRIPTION

FIG. 1 is a right, top, front perspective view of a tub for bathing embodying my new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a cross-sectional view thereof taken along line 7—7 of FIG. 2;

FIG. 8 is a bottom plan view thereof;

FIG. 9 is a left, top, front perspective view of a second embodiment;

FIG. 10 is a top plan view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a cross-sectional view thereof taken along line 15—15 of FIG. 10; and,

FIG. 16 is a bottom plan view thereof.

The broken line representations of holes in FIGS. 2, 4, 6-8, 10, 12, and 14-16 are for the purpose of illustration only, and form no part of the claimed design.
